UNITED STATES PATENT OFFICE.

EARL G. WATROUS, OF CHICAGO, ILLINOIS.

LIQUID-SOAP FIXTURE.

1,242,398.

Specification of Letters Patent.

Patented Oct. 9, 1917.

Application filed September 19, 1914. Serial No. 862,614.

To all whom it may concern:

Be it known that I, EARL G. WATROUS, a citizen of the United States, residing at Chicago, Cook county, Illinois, have invented 5 certain new and useful Improvements in Liquid-Soap Fixtures, of which the following is a specification.

My invention relates to a liquid soap fixture and the object thereof is to provide a 10 simple and efficient bracket or holder for the liquid soap receptacle and also to provide a receptacle of a form to advantageously coöperate therewith. The various 15 features of advantage and utility in my fixture will be apparent from the description hereinafter given.

In the drawings Figure 1 is a front elevation of my fixture; Fig. 2 a section on the line 2—2 of Fig. 1, but showing the rear 20 portion of the liquid soap receptacle in elevation; Fig. 3 a section on the line 3—3 of Fig. 2, and Fig. 4 a section on the line 4—4 of Fig. 1.

Referring to the present embodiment of 25 my invention as herein shown, the liquid soap receptacle 1 which may be of suitable dimensions, is preferably of the shape and contour shown in the drawings, the same having a spherical or convex front portion, 30 a straight vertical rear portion adapted to be placed against a suitable support and a converging or restricted top portion or mouth adapted to be closed by any suitable closure such as the flanged cap 2. In this 35 cap there is mounted the usual delivery spout 3 and the pumping mechanism including the depending tube 4 and piston or plunger 5. As this mechanism may be of any suitable character and as it forms no 40 part of my present invention, the same need not be further described.

The bracket consists of a wire which is here an endless or one-piece wire which is so bent that it is capable of properly engaging and supporting the receptacle when such bracket is attached to a support. As shown, this wire is bent into two V-shaped portions 6 adapted to correspond with the general contour of two opposite sides of the 50 receptacle and a lower or loop portion 7 adapted to engage the lower front side of the receptacle, preferably at the groove 1^a formed at the junction between the front spherical portion of the receptacle and the 55 depending portion 1^b thereof. The free ends of the wire are outwardly bent or turned

so as to engage the openings in the cap 2 as shown in detail in Fig. 3, so that the bracket and receptacle, together with the cap, are securely held together. The bracket is provided with suitable means for attachment to a suitable support, such means in the present instance consisting of an arched plate 8 having an opening 8^a to admit the wires 6 at the bottom of the V formed thereby. This plate is provided with a transverse opening 8^b through which passes suitable fastening devices such as the screws 9 entering the support, not shown. It will be understood that the cap is provided with a filling opening 2^a normally closed by a removable closure 10.

My invention provides a very simple and efficient bracket for attaching the liquid soap receptacle to a suitable support, which 75 bracket is also capable of securely holding the cap or closure for the mouth of the receptacle in position.

I claim:

1. In combination with a soap receptacle 80 formed with a vertical flat rear face adapted to seat against a wall, a bracket consisting of a continuous wire arranged to be attached at opposite sides of said vertical face of the receptacle to the wall and formed with a downward loop engaging the lower front side of the receptacle and having its free ends connected with the receptacle near its top.

2. In combination with a soap receptacle, 90 a bracket consisting of a continuous wire bent to form angular side portions engaging opposite sides of the receptacle and an intermediate downwardly and forwardly extending loop portion engaging the lower front 95 side of such receptacle, and means arranged at the angles of said side portions of the wire for attaching the bracket to a support.

3. In combination with a soap receptacle, 100 a bracket consisting of a continuous wire bent to form V-shaped side portions engaging opposite sides of the receptacle and a connecting portion engaging the lower front side of such receptacle, and means engaging 105 said side portions at the bottom of the V for attaching the bracket to a support.

4. In combination with a soap receptacle, 110 a bracket consisting of a continuous wire bent to form V-shaped side portions engaging opposite sides of the receptacle and a connecting portion engaging the lower front

side of such receptacle, and plates engaging the bottoms of said V's of the bracket for attaching the bracket to a support.

5. In combination with a soap receptacle, a bracket consisting of a continuous wire engaging the opposite sides thereof and a closure cap for the receptacle, the free ends of the wire being connected with the cap.

6. In combination with a soap receptacle, 10 a bracket consisting of a continuous wire engaging the opposite sides thereof and a cap which closes the receptacle and which is provided with openings on opposite sides, the free ends of the wire engaging in said 15 openings.

7. In combination with a soap receptacle, a bracket consisting of a continuous wire engaging the opposite sides thereof and a

cap which closes the receptacle and which has a flange fitting on the receptacle, said 20 flange having openings on its opposite sides into which the free ends of the wire enter.

8. In combination with a soap receptacle, a bracket consisting of a continuous wire bent to form V-shaped side portions engaging opposite sides of the receptacle and a connecting portion engaging the lower front side of such receptacle, a cap which closes the receptacle and to which the free ends of the wire are connected, and means engaging 30 said side portions for attaching the bracket to a support.

EARL G. WATROUS.
